United States Patent

Des. 240,595
Patented July 20, 1976

240,595

CONTAINER CLOSURE

Elmer E. Kress, 933B Heritage Village,
Southbury, Conn. 06488

Filed Mar. 25, 1974, Ser. No. 454,230

Term of patent 14 years

Int. Cl. D9—07

U.S. Cl. D9—164

FIG. 1

FIG. 2

FIG. 3

FIG. 4

FIG. 5

FIG. 6

FIG. 1 is a bottom perspective view of a container closure showing my new design;

FIG. 2 is a top perspective view;

FIG. 3 is a top plan view;

FIG. 4 is a bottom plan view;

FIG. 5 is a side elevational view;

FIG. 6 is a cross-sectional view taken through the center of the container closure.

I claim:

The ornamental design for a container closure, substantially as shown and described.
